UNITED STATES PATENT OFFICE.

ARTHUR S. WHEELER, OF BOSTON, MASSACHUSETTS, ASSIGNOR TO F. S. WEBSTER COMPANY, OF BOSTON, MASSACHUSETTS, A CORPORATION OF MAINE.

PENCIL-SHARPENING MACHINE.

961,392.

Specification of Letters Patent. Patented June 14, 1910.

Application filed March 9, 1909. Serial No. 482,342.

To all whom it may concern:

Be it known that I, ARTHUR S. WHEELER, of Boston, county of Suffolk, State of Massachusetts, have invented an Improvement in
5 Pencil-Sharpening Machines, of which the following is a specification.

This invention relates to pencil-sharpening devices and is an improvement upon the pencil-sharpening device shown in Letters
10 Patent #648,900, dated May 1, 1900.

It has for its object to provide a pencil-sharpening device with an improved adjustable stop arranged opposite the inner end of and in alinement with the pencil-receiving
15 orifice and adapted to extend under the cutter, against which the end of the lead of the pencil is adapted to bear, to thereby limit the inward movement of the pencil while it is being sharpened; also to provide im-
20 proved means for adjusting the stop axially; also to provide means for limiting the movement of said stop in opposite ways.

Figure 1, is a side elevation of a pencil-sharpening device embodying this invention.
25 Fig. 2, is a front view, the hood being removed. Fig. 3, is an enlarged longitudinal vertical sectional detail, showing particularly the adjustable stop involving this invention. Fig. 4, is a plan view of the parts
30 shown in Fig. 3. Fig. 5, is a detail of a portion of the head, showing particularly one of the entrance notches to the circumferential groove therein.

The general construction of the pencil-
35 sharpening device is the same as shown in the aforesaid patent. It comprises a stand A having a concavo-convex or cup-like head A' and a foot A'', said head having an elongated bearing a. A circular hood H is
40 adapted to fit on the head, it having a hollow base H'.

A rotatable carrier is provided for the pencil or other object to be sharpened or pointed, comprising a body-portion c, having at one end a journal-portion c', adapted to be supported by the head A', and made long enough to extend through the elongated bearing of said head and to receive upon its outer end a crank C. Said body-portion c
50 has at its opposite end a cylindrical portion c'', having a center hole extending longitudinally through it, and into the body-portion for a considerable distance, to form a pencil-receiving orifice. Said body-portion is
55 formed with a recess which intersects said

orifice and is adapted to receive a circular cutter d, having cutting teeth on its inner side or face adapted to engage a portion of the pencil projecting beyond the perimeter
60 of the orifice.

The shaft d' bearing the cutter d has its bearings in the body c, and a pinion d'' is secured to said shaft which engages an annular gear A' formed on or secured to the inner face of the head, so that when the carrier is rotated on its axis the disk d will be carried around therewith and also rotated on its own axis. The shaft d' is arranged obliquely to the axis of the carrier, so that the cutter d will occupy an oblique position
65 with respect to a pencil contained in the pencil-receiving orifice to engage the end thereof at an angle for the purpose of sharpening the same.

The journal-portion c' is herein shown as
70 formed with a cylindrical hole through it longitudinally from end to end which is arranged in alinement with the pencil-receiving orifice, the inner end of said hole opening into the recess in the body of the carrier. A cylindrical bar f is contained in said hole which is made long enough to extend therethrough and to project therefrom at each end. The inner projecting end of
75 said bar is slabbed off at an angle oblique to the axis of the carrier, or is shouldered, as at f', and its reduced end-portion thus formed extends beneath the cutter and terminates close to the inner end of the pencil-
80 receiving orifice, and extends over the center of said orifice so as to be engaged by the end of the lead of the pencil to be sharpened, serving as a stop therefor. The outer end of
85 said bar is reduced in diameter and has arranged on its reduced portion a sleeve g, which is free to turn thereon, the end of the bar being upset or riveted to hold said sleeve in place. Said sleeve is externally screw-threaded to engage internal screw-threads
90 formed on the interior of the journal-portion, and is provided at its outer end with a knurled head by which it may be turned. Rotary movement of said sleeve acts to move
95 the bar axially.

My invention is not limited to making the
100 stop in the form of a bar as here shown, or to providing it with a screw-threaded sleeve for the purpose of adjusting it axially. The bar is cut away at a point intermediate its length, as at f'', and a small screw f'' ex-
110

tends through the side of the journal-portion, the inner end of which enters said recess in the bar to thereby limit axial movement of said bar in opposite ways.

5 Having thus described my invention, what I claim as new and desire to secure by Letters Patent is:—

1. In a pencil-sharpening device, a rotatable carrier having a central longitudinal receiving-orifice, and a recess for the cutter intersecting said orifice at an angle oblique to the axis of the carrier, and a journal-portion at one end provided with a center-hole through it longitudinally, arranged 10 in alinement with said orifice, a bar arranged in said hole, the inner end of which is slabbed off at an angle oblique to the axis of the carrier and the reduced portion thus formed projects into said recess beneath the cutter and terminates close to the inner end and extends over the center of said orifice, to be engaged by the lead of the pencil, substantially as described.
2. In a pencil-sharpening device, a rotatable carrier having a central longitudinal receiving-orifice, and a recess for the cutter intersecting said orifice and a journal-portion at one end provided with a center hole through it longitudinally arranged in alinement 25 with said orifice, a bar arranged in said hole in the journal-portion, one end of which is reduced and projects into said recess beneath the cutter and terminates close to the inner end of said orifice, means for 30 adjusting said bar axially, and means for limiting axial movement of said bar in opposite ways, substantially as described.

3. In a pencil-sharpening device, a rotatable carrier having a central longitudinal receiving-orifice, and a recess for the cutter intersecting said orifice, and a journal-portion at one end provided with a center-hole through it longitudinally, arranged in alinement 40 with said orifice, a bar extending

through said center-hole, the inner end of which extends into said recess beneath the cutter and terminates close to and in front of the inner end of said orifice; and rotatable means connected with the outer end of said bar and engaging the journal-portion 50 for adjusting the bar axially, substantially as described.

4. In a pencil-sharpening device, a carrier having a longitudinal receiving-orifice and a recess for the cutter intersecting said orifice, and a journal-portion at one end provided with a hole through it longitudinally arranged in alinement with said orifice, and a bar extending through the hole in said journal-portion, the inner end of which projects into said recess and terminates close to the inner end of said orifice, and a screw-threaded sleeve arranged on said bar, at the outer end thereof, having a knurled head, the screw-threaded portion 60 of said sleeve engaging internal screw-threads formed on the interior of the journal-portion, substantially as described.

5. In a pencil-sharpening device, a carrier having a longitudinal receiving-orifice 70 and a recess for the cutter intersecting said orifice, and a journal-portion at one end provided with a cylindrical hole through it longitudinally, arranged in alinement with said orifice, a cylindrical bar arranged in 75 said hole in the journal-portion, the inner end of which is slabbed off and projects into said recess and terminates close to the inner end of said orifice, and means for adjusting said bar axially, substantially as described.

In testimony whereof, I have signed my name to this specification, in the presence of two subscribing witnesses.

ARTHUR S. WHEELER.
